(57) **CLAIM**

The ornamental design for a digimatic micrometer, as shown and described.

DESCRIPTION

FIG. 1 is a front, right and top side perspective view of a digimatic micrometer showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the portion marked '9' of FIG. 1.

The broken lines shown in the drawings represent portions of the digimatic micrometer that form no part of the claimed design.

The dot-dash broken lines encircling portions of the digimatic micrometer in FIG. 1 and illustrated in enlarged views in FIG. 9 form no part of the claimed design.
